W. L. DENIO.
FIRE ALARM SYSTEM.
APPLICATION FILED APR. 5, 1909.

1,008,960.

Patented Nov. 14, 1911.

UNITED STATES PATENT OFFICE.

WILLIAM L. DENIO, OF ROCHESTER, NEW YORK.

FIRE-ALARM SYSTEM.

1,008,960.

Specification of Letters Patent. Patented Nov. 14, 1911.

Application filed April 5, 1909. Serial No. 487,981.

To all whom it may concern:

Be it known that I, WILLIAM L. DENIO, of Rochester, in the county of Monroe and State of New York, have invented certain 5 new and useful Improvements in Fire-Alarm Systems; and I do hereby declare the following to be a full, clear, and exact description of the same, reference being had to the accompanying drawings, forming a 10 part of this specification, and to the reference-numerals marked thereon.

My present invention relates to fire alarm systems in which the alarm is given by an 15 automatic mechanism or call box which is electrically controlled and in which the operating circuit is completed by means of thermostatic devices.

The invention has for its object an arrangement of circuits which will minimize 20 the liability of sounding an alarm from accidental causes together with means whereby the various circuits may be tested without actuating the alarm mechanism *per se*.

To these and other ends the invention 25 consists in certain improvements and combinations of parts all as will be hereinafter more fully described, the novel features being pointed out in the claims at the end of the specification.

30 In the drawings: Figure 1 is a diagrammatic illustration showing the preferred arrangement of the various parts of apparatus arranged in accordance with my present invention, and, Fig. 2 is a similar illustration 35 showing a modification.

Devices embodying my present invention are adapted to be used in conjunction with 40 fire alarm calling or signaling boxes or impulse transmitters of the usual or any preferred construction which are designed to be normally set for operation and released by a flow of current in the energizing or controlling circuit. In connection with mechanism of this character it is important that

45 the circuit controlling the operation of the signal box be so arranged that it may not be accidentally set into operation and as these circuits may be of considerable length and be extended through numerous rooms 50 and different floors of a building for connecting a comparatively large district with one signal box, it is essential that adequate means be provided whereby the controlling circuit may be tested as a means of demonstrating the fact that it is at all times in

operative condition without releasing the signaling box during such tests.

In order to illustrate my present invention, I have shown it in connection with a signaling device or calling box, indicated by 60 A, and comprising a toothed member or number wheel 1 which is adapted to be driven by a clock train, actuated by a spring (not shown), and comprising an escapement wheel 2 with which cooperates a verge 3 65 normally locked by a trip 4. Cooperating with the number wheel 1 is a contact spring 5 which is connected by a wire 6 forming one leg of the fire alarm circuit B, the wire, indicated by 7, forming the other leg of 70 the bridge being in electrical connection with the frame of the signaling device. The latter may be associated with a telephone circuit leading from a residence or building, or such circuit may extend directly to the 75 fire department headquarters.

The trip 4 which interrupts the vibration of the verge acts as a restraining member and while in the preferred structure shown in Fig. 1, the trip is shown as being connected to the armature 8 of an electromagnet, it will be understood that the mechanism of the call box may be restrained by other forms of electrically operated devices which will be actuated when a flow of current thereto is permitted.

In carrying out my invention I provide a conductor leading from the restraining device in which is interposed a source of current such as the battery B'. The second 80 conductor over which the circuit is completed also leads from the restraining device but is not in electrical connection with the first mentioned conductor, these two main conductors being connected by thermostatic devices which when actuated or set into operation, by being heated to a predetermined temperature, will complete the 85 electrical circuit.

It has been demonstrated by experience 100 that alarms are sounded unnecessarily when two parallel conductors have been employed, as it frequently happens that an incipient fire which will actuate a single thermostat will be extinguished by persons on the 105 premises so that the sending in of the alarm might have been obviated. Further, it is not an infrequent occurrence that a thermostatic device is accidentally operated or "touched off" by means other than an actual 110

conflagration, thus adding another source of complaint against the proper operation of fire alarm systems of this character. In order to obviate these disadvantages and 5 also to remove other causes of criticism, which it is not necessary to mention specifically, I provide a new and novel means of preventing the accidental release of the signaling device or calling box by arranging 10 in conjunction with the main conductors before mentioned, a secondary conductor and this I connect by means of the thermostatic devices to each of the main conductors. The thermostats I arrange in pairs, those of 15 each pair being separated but arranged in such a position, one to the other, as in the same room or compartment of a building, that a conflagration occurring in proximity to one of them will actuate both thermostatic 20 devices in the event it is not extinguished and acquires headway sufficient to threaten the entire room or its contents. My invention also comprehends the arrangement of the two main conductors and the secondary 25 conductors in the form of loops and providing in the latter switches, and contacts with which they coöperate, said switches being capable of adjustment to cut out or disconnect the retaining mechanism of the signaling 30 device and bring into circuit with the loops indicating devices, such as bells or buzzers, which will then be operated to indicate whether or not the loop circuits are intact throughout the building in which they 35 are arranged, the operation of these indicating devices under certain conditions also enabling the operator to determine whether or not any of the thermostatic devices have been actuated and should be replaced by 40 new ones. The arrangement of the circuits I have thus described generally will be understood from an inspection of Fig. 1 in which the electrically operated retaining device governing the movement of the fire 45 alarm signaling box is illustrated as an electromagnet 9. The main conductors indicated by C and D are arranged to form the loops C' and D' which it will be understood, may be extended over any desired territory 50 or district which it is desired to connect with the signaling mechanism A. The secondary conductor is arranged parallel to the main conductors and for convenience in illustration is shown as located intermediate the latter. This conductor is indicated by E 55 and is connected by a plurality of thermostatic devices e with the main conductor C' and by similar devices, indicated by e', with the main conductor D'. It will be understood 60 that the thermostats e and e' are associated in pairs and may be located in proximity to each other at various points in the loops of the conductors.

The testing switch before referred to is 65 indicated by F and comprises the switch

arms 10, 11, 12 and 13 which are pivoted on the posts 10^a, 11^a, 12^a and 13^a and normally engage the contacts 10^b, 11^b, 12^b and 13^b. These switch arms are connected for simultaneous operation and when revolved, 70 coöperate with the contact sockets 10^c, 11^c, 12^c and 13^c. The loop of the secondary conductor E is normally closed through the switch arm e² which rests in engagement with the contact e³, said switch arm being 75 also adapted to engage the contact e⁴ connected by the wire e⁵ with an indicating device e⁶ from which said conductor is extended, as indicated at e⁷, to one side of a battery B², the other pole thereof being connected by the wire e⁸ to the contact e³. 80

The battery B' is connected by a branch d with the post 12^a, the main conductor D of which this branch is a part, being connected to the switch contact 12^b. The remainder of the circuit formed by this conductor, which comprises the loop D', receives current from the opposite pole of the battery B' over the branch wire d' in which is inserted the indicator d² and from which 90 leads the wire d³ to the switch contact 10^b forming one terminal of the loop D' the other extremity thereof being connected to the switch post 10^a. The loop C' of the other main conductor C is completed through the switch arm 11, one end of the loop terminating at the post 11^a, the other extremity thereof being formed by the wire c joined to the switch contact 11^b. 95

For the purpose of testing the continuity 100 of the loops a wire d⁴ is tapped to the loop D' and connected by leads d⁵, d⁶, and d⁷ with the switch contacts 10^c, 11^c and 13^c respectively, and a similar tap c' leads from the wire c to the switch contact 12^c. Under 105 normal conditions the switch F occupies the position shown in full lines and there is no current flowing over the main conductors C, D, but when any two thermostats constituting a pair of conductor connectors are actuated, a circuit will be established over the following path:—battery B', wire d, switch post 12^a, blade 12, contact 12^b, conductor D, magnet 9, conductor C, (loop C') thermostat e, conductor E, thermostat e', loop conductor D', switch contact 10^b, wire d⁸, in 110 wire d', battery B'. The current which traverses the circuit just described actuates the magnet 9 to retract the latch, or trip, 4 and permit the alarm box to be set into operation. If the switch F is operated the magnet 9 is cut out of the circuit and the following results will occur, providing the loop 115 circuits are all intact. The switch arms 11 and 12 engage the contacts 11^c and 12^c when the following circuit may be traced:—battery B' wire d, switch post 12^a, arm 12, contact 12^c, wire c', loop C', switch post 11^a, arm 11, contact 11^c, wire d⁸, d⁴, loop D', contact 10^b, wire d⁸, indicator d², wire d' to 120 125

130

battery B'. The loops C' and D' of both the main conductors being continuous throughout their length will cause the indicating device or bell d^2 to sound but as its operation is rendered impossible if either of said loops is broken, this fact may be easily determined in this manner. Likewise, the continuity of the loop formed by the secondary conductor E may be tested by moving the 10 switch e^2 in engagement with the contact e^4 when current will be permitted to traverse the conductor illustrated in heavy lines in Fig. 2 to effect an operation of the indicating device e^6 . The switch e^2 however is normally in engagement with the contact e^3 , as shown in full lines, but as the conductor e^5 is connected with the switch post 13^a the indicator e^6 will be operated when the switch arm 13 engages the contact 13^c, in the event 15 any of the thermostatic devices have been operated, as they will permit current to traverse either of the following paths:—battery B², wire e^8 , loop E, thermostat e' , loop conductor C', switch post 11^a, arm 11, contact 11^c, wires d^6 , d^4 , d^7 , contact 13^c, arm 13, post 13^a, wire e^6 , indicator e^6 , wire e^7 , battery B²; or, battery B², wire e^8 , loop E, thermostat e' , loop conductor D', switch post 10^a, arm 10, contact 10^c, wires d^6 , d^4 , d^7 , contact 13^c, arm 13, post 13^a, wire e^5 , indicator e^6 , wire e^7 , battery B².

In Fig. 2, I have shown substantially the same arrangements of the parts as those previously described, with the exception that in 35 lieu of the magnet 9 I have shown a fuse or heat coil G for restraining the action of the alarm box, which is designed to be destroyed by an excessive flow of current. In this figure the main conductors leading from the 40 battery B³ are indicated by C¹⁰ and D¹⁰, the secondary conductor being also indicated by E¹⁰. As it is not essential that the conductors be arranged in loop form as shown in Fig. 1 in order to carry out that part of 45 my invention relating to the use of an intermediate conductor in conjunction with thermostats arranged in pairs, I have in this figure shown all of the conductors as arranged parallel to each other in straight 50 lines.

Circuits for fire alarm systems arranged in the manner described possess not only the advantage of reducing to the minimum the liability of releasing the fire alarm signaling 55 device or calling box accidentally but they may also be tested periodically by those in charge so that the fact may be known that they are at all times in proper operative condition.

60 I claim as my invention:

1. An alarm system comprising an alarm mechanism, an electrically operated device having terminals and controlling the operation of said mechanism, two separate conductors leading from the terminals of said

device, and a third conductor, a source of current connected to one of said conductors and means for connecting the third conductor to both of the other conductors to complete an electric circuit through them. 70

2. The combination with a fire alarm signal mechanism and devices for restraining its operation embodying an electromagnet and a source of current supply, of electrically separated main conductors leading 75 from the source of supply adapted to connect it in circuit with the magnet, a secondary conductor and thermostatic devices uniting it to each of the separated conductors, said secondary conductor and thermostatic devices being adapted to complete the circuit between the main conductors. 80

3. The combination with a fire alarm signal mechanism which is normally set in operative condition and an electrically operated device for restraining its operation, adapted to be actuated to release said mechanism by a flow of current, of a source of current, electrically separated main conductors leading therefrom and adapted to connect it to the restraining device, a secondary conductor and thermostatic devices arranged between it and each of the main conductors which when operated are adapted to complete a circuit through the main conductors. 95

4. The combination with fire alarm signal mechanism which is normally set in operative condition and an electrically operated device for restraining its operation adapted to be actuated to release said mechanism by 100 a flow of current, of a source of current, two electrically separated main conductors leading therefrom and adapted to connect it with the restraining device, each of said conductors forming a closed loop, a third or secondary conductor, thermostatic devices arranged alternately between the two loops and the secondary conductor adapted to electrically connect the two loops through 105 said secondary conductor, switches interposed in the conductors for disconnecting them from the restraining device, contacts with which said switches engage, devices arranged in circuit with said loops and contacts for testing the continuity of the loops. 110

5. The combination with a fire alarm signaling mechanism which is normally set in operative condition and an electrically operated device for normally restraining its operation, which is adapted to be actuated to release said mechanism by a flow of current, of a source of current supply, two main conductors leading therefrom and adapted to connect it with the restraining device each of which is provided with a 120 loop portion, a secondary conductor also provided with a loop portion, separate thermostatic devices connecting the secondary conductor at various separated points to the loop of each main conductor and switches 125 130

interposed in the three conductors for disconnecting the circuit of the restraining device, contacts with which said switches co-operate, indicating devices located in circuit with the loops of the two main conductors and their contacts for indicating the continuity of said loops and testing the condition of the thermostats and a separate in-

dicating device located in the circuit of the loop of the secondary conductor for indicating its continuity. 10
